UNITED STATES PATENT OFFICE

147,704

DESIGN FOR A HAND LUGGAGE CASE

George Henry Wheary, Jr., Racine, Wis., assignor to Wheary Incorporated, Racine, Wis., a corporation of Wisconsin

Application January 9, 1947, Serial No. 136,025

Term of patent 14 years

(Cl. D87—3)

To all whom it may concern:

Be it known that I, George Henry Wheary, Jr., a citizen of the United States, residing at Racine, in the county of Racine and State of Wisconsin, have invented a new, original, and ornamental Design for a Hand Luggage Case, of which the following is a specification, reference being had to the accompanying drawing, forming part thereof.

Figure 2 is a side elevational view of the case showing the appearance thereof from either side, both sides being identical in appearance;

Figure 3 is an end elevational view of the case showing the appearance thereof from either end, both ends being identical in appearance.

The dominant features of my design are shown in full lines.

I claim:

The ornamental design for a hand luggage case, substantially as shown and described.

GEORGE HENRY WHEARY, JR.
